UNITED STATES PATENT OFFICE.

FREDERICK W. PEISCH, OF CHICAGO, ILLINOIS.

BOTTLE-COVER.

1,103,827.

Specification of Letters Patent. Patented July 14, 1914.

Application filed January 19, 1914. Serial No. 813,052.

To all whom it may concern:

Be it known that I, FREDERICK W. PEISCH, a citizen of the United States, and a resident of the city of Chicago, county of Cook, and 5 State of Illinois, have invented certain new and useful Improvements in Bottle-Covers, of which the following is a specification.

My invention relates to improvements in bottle covers especially adapted for use in conjunction with milk bottles and also adapted to serve as a means for removing the ordinary cardboard disk used as a closure for said bottles, the object of the invention being to provide a simple and efficient device of 15 this character.

The invention consists in the combinations and arrangements of parts hereinafter described and claimed.

The invention will be best understood by 20 reference to the accompanying drawing forming a part hereof and which is a sectional view taken through the mouth of a milk bottle showing a device embodying my invention in position of use.

25 The preferred form of construction as illustrated in the drawing comprises a circular metallic disk or plate 1 adapted to be inserted within the mouth of an ordinary milk bottle 2 and resting flat upon the usual 30 cardboard closing disk 3 as indicated. The disk 1 is provided with a central upwardly extending recess 4 and a cork screw member 5 made of spring wire and is mounted in said recess for limited longitudinal movement therein and projecting therefrom. The upper end of cork screw member 5 is provided with an operating handle 6 to facilitate manipulations thereof and of the cover itself. At its outer edge disk 1 is provided 35 with a raised edge flange 7 which is adapted to fit against the edges of the mouth of bottle 2 and serve as a supplemental seal therefor.

40 In use, when it is desired to remove the closure 3, the disk 1 is inserted in the mouth of the bottle to rest flat against said closure. Then handle 6 is pressed downwardly and turned until cork screw member 5 punctures the closure 3 and draws the same tightly 45 against the bottom of disk 1 where it will be

held by the spring action of the spring wire 50 in the cork screw member 5, the limited longitudinal movement of cork screw member 5 permitting of such adjustment and manipulation. The arrangement of the parts is such that when closure 3 has thus 55 been secured to disk 1, flange 7 will rest snugly against the upper edge of the bottle mouth to constitute a supplemental seal in case the closure is replaced. By this arrangement, when it is desired to reseal the 60 bottle, the closure 3 operates as a washer for the cover disk 1 so that a double seal is obtained. It will also be observed that the puncture caused by the cork screw member through the closure 3 is completely inclosed 65 by the disk 1 and thus sealed from the outside air and any leakage through said puncture is also prevented from escape.

While I have illustrated and described the preferred form of construction for carrying 70 my invention into effect, this is capable of variation and modification without departing from the spirit of the invention. I, therefore, do not wish to be limited to the precise details of construction set forth, but 75 desire to avail myself of such variations and modifications as come within the scope of the appended claim.

Having described my invention what I claim as new and desire to secure by Letters 80 Patent is:

A bottle cover comprising a cover member adapted to fit within the mouth of a bottle to rest upon the ordinary closing disk therein and provided with a central recess and a 85 raised edge flange adapted to contact with the edges of the bottle mouth; and a spring wire cork screw member mounted for limited longitudinal movement in said recess and projecting therefrom, substantially as described.

In testimony whereof I have signed my name to this specification in the presence of two subscribing witnesses.

FREDERICK W. PEISCH.
